UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

JUSTIFICATION-SPACE-INDICATING MECHANISM.

1,283,623.

Specification of Letters Patent.

Patented Nov. 5, 1918.

Application filed February 28, 1916. Serial No. 81,065.

To all whom it may concern:

Be it known that we, JOHN SELLERS BANCROFT and MAURITZ C. INDAHL, citizens of the United States, residing at Philadelphia, in the county of Philadelphia and State of Pennsylvania, have invented certain new and useful Improvements in Justification-Space-Indicating Mechanism; and we do hereby declare the following to be a full, clear, and exact description of the same, reference being had to the accompanying drawings, forming part of this specification.

This invention relates to machines for preparing or composing controllers or record strips for automatic typecasting and similar machines, which embody in their organization line measuring and line-justification mechanisms. The invention refers more particularly to the line justification indicating mechanism, and has for its chief object to improve or simplify the construction of part of this mechanism.

The machine to which the invention is particularly applicable is that disclosed in Patent No. 944,405, Dec. 28, 1909, and the invention is an improvement on certain parts of the justification mechanism described in the above specification and shown in the drawings annexed thereto.

According to the machine described in the specification of said patent, the unit or set value of each character or space is recorded by a line measuring mechanism and as each justification space is registered or recorded there is operated a space counter which moves in relation to a justification indicator or chart so that the justification fraction necessary for the justification of the composed line may be readily ascertained by the operator. It is not deemed necessary to give a detailed description of the line indicating justification mechanism set forth in the aforesaid patent as such mechanism is now in common use, and a detailed description thereof can also be obtained by reference to the patent. It is sufficient for the present purpose to state that the justification space counter comprises a longitudinally moving bar furnished with a pointer and a rack or teeth. One or more lifting pawls which engage the teeth are controlled by a motor which is operated automatically to raise the

bar each time a justification space key is actuated.

As is stated in the aforesaid patent, it is undesirable that more than a certain number of justification spaces should be inserted in any particular line of composition, and in order to relieve the operator of the necessity of paying particular attention to the number of justification spaces he inserts, automatic mechanism is provided whereby when the space counting bar has moved a certain distance, corresponding to a particular number of justification spaces, it acts on mechanism, which, should further justification spaces be inserted by the operator, will prevent these additional spaces from being recorded as justification spaces on the line measuring and indicating mechanism, and the punches for a justification space will not be operated. In other words, this automatic mechanism transfers the signal for a justification space to an ordinary space, and the value of the ordinary space is recorded by the line measuring and indicating mechanism.

In the machine according to the patent above mentioned the number of justification spaces which can be recorded before the automatic cut-out becomes effective is a fixed one, but in the commercial machine it has been found desirable to provide a hand controlled device whereby the transferring of the signal producing devices and the indicating devices from a justifying to a non-justifying space can be controlled at the will of the operator and become effective after any number of justifying spaces have been recorded. The previous construction has a disadvantage in that it renders it a relatively difficult and lengthy operation to remove the space counting bar or to disengage it from the hand controlled and automatic mechanisms when it is desired to remove the bar for cleaning, renewal, or other purposes.

It is the chief object of the present invention to so construct the parts coöoperating with, acting upon, and operated by the space counting bar, that the latter can be removed readily and easily when required, without the necessity of removing or interfering with adjacent parts.

The automatic shift and throw-out mechanism as heretofore employed, comprises a

shift valve controlling the punch actuating motors and the space-counting bar motor, which valve is acted upon by a lever adapted to be operated by the space-counting bar 5 and also arranged to be operated by a longitudinally movable bar controlled by a hand actuated rod or device.

According to the present invention there is interposed between the shift-valve controlling lever and the space bar a connector member which in its normal position is actuated upon by the space bar and the hand operated bar to operate the lever, and so contrived that it can be moved relatively to the controlling lever to be disengaged from and release the space-counting bar to allow the latter to be removed from the machine but when released it will automatically take up its normal position again.

20 Referring to the accompanying drawings:

Figure 1 is a perspective elevation of the space counting bar and the parts connected with it, and, apart from the hand controlled device above referred to, the mechanism 25 agrees practically with that described and illustrated in the aforesaid patent.

Fig. 2 is a detailed view of part of the mechanism shown in Fig. 1.

Fig. 3 is a view similar to Fig. 1 showing 30 the improved connection intermediate the valve operating lever and space-counting bar.

Fig. 4 is a sectional diagrammatic view illustrating the mechanism shown in Fig. 3.

35 Like characters of reference throughout the several figures indicate the same parts.

85 is the space counting bar. 86 and 87 the lifting and holding pawls acting on the teeth *a* of the bar 85 and controlled by the 40 motor 90. 198 is a valve controlling through the shift valve, the transference of the signal from the punches for the justifying space to those of the non-justifying space. 201 is the valve operating lever acting upon the 45 valve 198 and 200 a hook connecting the lever 201 with the bar 85. The parts thus far described and the reference numbers indicating such parts correspond to the parts, and indicating numbers in the aforesaid pattern to which reference may be had for a description and illustration of coöperating parts of the machine.

10 is a vertically movable bar adapted when elevated to engage the hook 200 and through 55 it to move the lever 201 and valve 198. This bar 10 is manually controlled through the medium of a knob or finger piece or rod 11 mounted to slide in bearings in the frame and provided with a cam or inclined face 12 for coöperation with the lower end of the 60 bar 10.

Referring now to Figs. 3 and 4 it will be seen that a lever 201^a is substituted for the lever 201 of the prior arrangement shown in Fig. 1 and upon the inner end of this lever

there is pivoted at 14 a three arm lever, one arm 13 of which forms a finger piece while the arm 15 is adapted to rest on the lever 201^a and the arm 16 projects into position to coöperate with the shoulder 17 on the space 70 bar 85 and to be acted on by the upper end of the manually controlled bar 10. The three armed lever forms a releasable extension of the lever 201^a and may be tripped to move the arm 16 out of the path of the 75 shoulder 17 on the space bar by moving the arm 13 upwardly. Such movement causes the lever 201^a to tilt on its pivot slightly and the rod 10 to move laterally at its upper end, the rod being loosely mounted in its guide 80 frame to permit of such lateral movement.

In the mechanism, as shown in Fig. 1, each time a justification space key is actuated by the operator, air passes to the motors of the justification space-punches and 85 also to the motor 90 acting on the arm 91 raises the lifting pawl 86, which, engaging the teeth of the justification space counting bar 85, raises the latter through one division. Should the operator, after the predetermined number of justification spaces that are to be placed in a line is reached, again touch the justification space key, the bar 85 in rising will lift the hook 200 through the engagement of shoulder 17 on the bar with 95 the nose of the hook, and the hook will cause the lever 201 to be turned on its fulcrum *d* and operate the valve 198. The valve 198, when so operated allows air to pass to shift the valve 20 so as to close the communication 100 of the space signal keys with the space signal punch motors, and transfer the communication to the punches of an ordinary space. The motor 90 receives its motive fluid through one of the justification punch motors, so that when the power is shut off from this motor by the operation of valve 20, no further movement of the bar 85 can take place.

Should the operator, before the predetermined number of justification spaces has been reached, desire to prevent further justification spaces from being recorded in the line, he moves the rod 11 in the direction of the arrow in Fig. 1, so that the cam or inclined surface 12 on this rod engages the end of the rod or bar 10 and raises it. The raising of the bar 10 brings its upper end into engagement with the hook 200 and elevates it, thereby operating the lever 201 120 and the valve 198 in the same manner as if the hook had been elevated by the bar 85.

The connection of the bar 10 with the hook 200 is shown clearly in Fig. 2. As the nose of the hook is in the path of the shoulder 17 on the bar 85, the bar cannot be removed without the hook being first removed. The hook cannot be removed until the bar 10 has been removed, so that if it is desired to remove the space counting bar, 130

several parts of the machine have to be first removed.

With the mechanism of the present invention as shown in Figs. 3 and 4, the hook 5 is dispensed with, and the releasable extension is mounted on the lever 201^a. With this arrangement when the predetermined number of justifying spaces have been inserted in the line the shoulder on the bar 10 85 engages the nose of the arm 16, and the continued upward movement of the bar carries the lever 201^a with it to operate valve 198, since the arm 15 resting on the lever 201^a prevents the three armed lever from 15 turning on its pivot.

Similarly, should the operator move the rod 11 the bar 10 is lifted, and in rising engages the lever arm 16 to raise it and turn the lever 201^a upon its pivot. 20 When it is desired to remove the bar 85 it is only necessary to turn the three armed lever on its fulcrum by pressing the third arm 13 upwardly. Such pressure on the arm 13 will cause the lever 201^a to tilt and 25 will move the rod 10 laterally slightly and the arm 16 will be turned clear of the bar 85, thereby permitting the bar 85 to be removed quickly and easily and without disturbing or removing or disassembling any 30 other parts of the machine. Moreover, the connector lever, when released, as after the bar 85 has been withdrawn, automatically takes up a position ready to slip over the shoulder 17 without manipulation on the 35 part of the operator when the bar 85 is returned to its holder.

We claim:—

1. A mechanism such as described embodying a removable justification space 40 counting member, means for moving said member in accord with the number of justification spaces designated, a member for interrupting the formation of justification space indications, a connector intermediate 45 said members, adapted to be manually placed in disconnecting position whereby the counting member may be removed, and em-

bodying means for automatically returning it to connecting position when released from manual control. 50

2. A mechanism such as described embodying a removable justification space counter bar, means for moving said bar in accord with the number of justification spaces designated, a lever for interrupting 55 the formation of justification space indications, a connector carried by the lever and normally projecting into the path of the bar, said connector adapted to be positioned manually temporarily out of its normal position, whereby the counter bar may be removed, and embodying means for automatically returning it to said normal position when released from manual control. 60

3. A mechanism such as described embodying a removable justification space bar, means for moving said bar in accord with the number of justification spaces designated, a lever controlled by said bar for interrupting the formation of justification 70 space indications, a manually controlled bar for moving said lever, a connector intermediate the lever and bars, adapted to be moved manually temporarily to disconnecting position whereby the space bar may be 75 removed, and embodying means for automatically returning it to connecting position when released from manual control. 80

4. A mechanism such as described embodying a removable justification space bar, means for moving said bar in accord with the number of justification spaces designated, a lever controlled by said bar for interrupting the formation of justification space indications, a second lever mounted on 85 said first mentioned lever, said second lever having an arm projecting into the path of the space bar and an arm resting on the first mentioned lever, and being capable of being moved to turn the first mentioned 90 arm out of the path of the bar to permit of the removal of the latter. 90
